(57) CLAIM

The ornamental design for a bowl as shown and described.

DESCRIPTION

1. Bowl

1.1 : Perspective

1.2 : Front

The design refers to a bowl; the form of the bowl is cylindrical and the outside surface of the bowl is surrounded with a geometric pattern; the diameter of the bowl narrows slightly to the opening; the diameter of the base of the bowl is narrower than the body.

The broken lines and the de-emphasized or half-toned portion shown within the broken lines in 1.1 depict a portion of the bowl that forms no part of the claimed design.
